BATHROOM FIXTURE

Harry Karp, Atlantic Beach, N. Y.

Application July 28, 1949, Serial No. 107,308

3 Claims. (Cl. 4—7)

1

This invention relates to bathroom fixtures and particularly to an improved compact personal hygiene device that is concealed from view when not in use.

This invention may be briefly described as an improved compact bathroom appliance, incorporated into a bathroom fixture having a water drainage system, for providing an extensible, uniform flow supply of temperature regulatable, medicament treated water for douche, enema, or other personal hygiene purposes, together with an integral concealed receptacle to contain the retracted device when not in use.

A primary object of this invention is the provision of an improved personal hygiene device.

Another object of this invention is the provision of an improved bathroom appliance including an extensible and retractible conveyer for a supply of water for personal hygiene purposes.

Another object of this invention is the provision of a personal hygiene device including means for supplying a uniform flow of temperature regulated water.

Another object of this invention is the provision of an improved personal hygiene device having a water conveying member coiled on a concealed tensioned reel for automatic retraction when not in use.

Another object of this invention is the provision of an improved personal hygiene device including means for introducing medicaments into the flow of water.

Another object of this invention is the provision of an improved personal hygiene device permanently incorporated into a bathroom fixture having a water drainage system.

Still another object of this invention is the provision of a readily available personal hygiene device incorporated into a bathroom fixture having a water drainage system, and which, when not in use, will be concealed from view.

A further object of this invention is the provision of an improved personal hygiene device having a nozzle movably mounted at the terminus of the water conveying apparatus.

Referring to the drawings:

Fig. 1 shows the incorporation and positioning of the invention in a bathroom fixture.

Fig. 2 shows the incorporation and positioning of the invention in another bathroom fixture.

Fig. 3 is a side view, partially in section, of the invention as incorporated into the bathroom fixture shown in Fig. 1. Fig. 4 is a view taken along line 4—4 of Fig. 3.

2

In Figs. 3 and 4, which are not drawn to scale for the purposes of clarity and ease of explanation, the improved personal hygiene device is shown as incorporated into a water closet adjacent a bathroom fixture of the type generally illustrated in Fig. 1. The water closet shown may be of a generally conventional shape and the walls 10 and 12 thereof, cooperating with the base section 14 to form a generally rectangular water reservoir. The water closet is formed of a suitable vitreous material as conventionally utilized for bathroom fixtures of this type and retains a supply of water 16 available for use in the adjacent bathroom fixture.

15 A supply of water for the personal hygiene device may be suitably introduced into the water reservoir through the base section 14 by a hot water supply pipe 18 and a cold water supply pipe 20. A suitable water tight joint at the junction of the pipes 18 and 20 and the base section 14 of the water closet may be formed by the packing members 22 being secured in watertight engagement against the surfaces of the base section 14 by the washers 24 and nuts 26 threadedly 20 mounted on the pipes. Each of the water supply pipes may be provided with a suitable check valve or vacuum breaking valve, as indicated at 27, or water may be supplied to the device from open tanks.

25 The hot and cold water supply pipes 18 and 20 extend upwardly inside the water reservoir and enter a mixing chamber 28, positioned above the water in the reservoir, through suitable water-tight joints, such as that shown at 30. The pipes 18 and 20 are then turned and connected to a mixing valve member 32. The mixing valve 32 is of a conventional construction of the type commonly utilized in shower installations and the like. The mixing valve 30 may be set to provide any desired water temperature or may completely close off the hot and cold water supplies. The valve member 32 is provided with a common outlet spigot 34 which is disposed within and introduces the water into the mixing chamber 28.

30 40 45 The mixing chamber 28 provides an efficient receptacle wherein the mixed hot and cold water, introduced therein through the mixing valve 32, may reach a temperature equilibrium and in which any surging due to variations of the water pressures in the pipes 18 and 20 may be eliminated.

45 Disposed adjacent the bottom portion of the mixing chamber 28 is an outlet 36 to which is 50 connected a suitable pipe or hose 38 by the cou-

pling member 40. The hose 38 conveys the liquid from the mixing chamber 28 and introduces it into the hollow portion 42 of the shaft 44.

The lower end of the shaft 44 is provided with a flange 46 which abuts and is supported by a supporting member 48 having a shaft encompassing terminal portion 50. Beneath the flange 46 and on the portion of the shaft 44 that extends through the terminal portion 50, the shaft is threadedly engaged and secured by the locking nut 52. The locking nut 52, the terminal portion 50 and the flange 46 cooperate to mount the shaft 44 securely in an upright position. The supporting member 48 is provided with a flanged mounting 54 which may be suitably affixed to the rear wall 18 of the water closet above the water 16 contained therein.

The hollow portion 42 of the shaft 44 is closed at its lower end by a plug 55 threadedly engaged with the terminus of the shaft. Rotatably mounted on the shaft 44 and supported by an abutment 56 thereon is a reel 58. The hollow portion 42 of the shaft 44 extends upwardly past the abutment 56 seating the reel 58 and is provided at its terminus with a plurality of openings, such as 60, through the shaft 44. Abutting the openings 60 in the shaft 44 is an annular chamber 62 formed by the webs 64 and 66 which engage the periphery of the shaft 44. Contained within these webs 64 and 66 are packing members 68 to prevent leakage of liquid from the chamber 62 between the shaft 44 and the webs 64 and 66. The chamber 62 is provided with an opening 70 which connects said chamber with an elongated annular chamber 72 formed by the wall members 74 and 76 of the reel 58. The elongated chamber 72 is provided with an outlet 78 in the lower portion thereof. Coupled to the outlet 78 through a coupling member 80 is one end of a length of flexible hose 82 coiled upon the reel 58. The upper extremity of the shaft 44 supports a positioning plate 84 having an abutment 86 on the periphery thereof which engages the wall member 76 of the reel 58 and positions the reel thereby.

The above described construction provides for a continuous transfer of water from the mixing chamber 28 to the hose 82 coiled upon the reel 58, while the reel 58 is rotating and irrespective of the rotative position of the reel 58 upon the shaft 44. In summary, the water flows from the mixing chamber 28 to the hollow portion 42 of the shaft 44 through the connecting member 38, the water flows from the hollow portion 42, through the plurality of openings such as 60 into the small annular chamber 62, from there through the opening 70 into the elongated chamber 72 and from thence to the hose 82 through the outlet 78.

Associated with the reel member 58 is a coil spring 88 contained in the space between the wall 76 and the shaft 44 between the positioning plate 84 and the upper web 64. One end of the spring is secured to the reel 58 and the other end thereof to the shaft 44 so as to automatically rewind the hose 82 on the reel 58 after extension therefrom.

The forward end 90 of the hose 82 is attached, in an expanded fitting, to a rigid member 92. The rigid member 92 is slidably contained within a sleeve 94. The sleeve 94 traverses the mixing chamber 28 and is secured in position by a flange 96 outwardly abutting the wall portion 98 at one end and a locking nut 100 threadedly engaging the opposite end adjacent the outer surface of the mixing chamber 28. The joints between the sleeve member 94 and the mixing chamber 28 are suitably constructed as to prevent leakage of

liquid therefrom and includes suitable packing, such as 102. The sleeve 94 is sized to permit the hose 82 to pass therethrough.

The rigid member 92 terminates in a spherically shaped socket 104. Adjacent the socket 104 is a gate valve 106 for stopping the flow of water through the member 92. The valve 106 is normally maintained in the "open" position by the spring 108. An abutment 110 is also provided in the rigid member 92 and cooperates with the exterior of the flange 96 on the sleeve 94 to limit the movement of the rigid member 92 therein.

Cooperating with the socket 104 is a connecting member 112 having one spherically shaped end 114 and one straight externally threaded end 116. The spherically shaped end 114 cooperates with the socket 104 to form a globe type or spherical joint for permitting relative motion therebetween.

Connected in removable threaded engagement with the threaded end portion 116 is a nozzle 118. Included in the nozzle 118, illustrated in the drawings, is an enlarged chamber 120 for medicaments, such as salts or crystals of a medicinal nature. The chamber 120 is provided with a strainer 122 or screen to prevent the passage of undissolved medicament therethrough. The chamber 120 is also provided with an opening 126 for the introduction of the medicaments therein, said opening being provided with a removable plug 128.

Although the drawing illustrates a nozzle suitable for douche purposes, it is within the contemplation of the invention to utilize other nozzles for other purposes, such as a nozzle to provide a spray for rinsing the hair after washing, etc.

The nozzle 118 and the members adjacently associated therewith are disposed within a recessed receptacle 130 in the front wall 12 of the water closet. The recess is sized to also contain a handle 132 for manually manipulating the mixing valve 32 to adjust the water temperature. The recessed receptacle 130 is integrally formed with the water closet. The receptacle 130 is provided with a cover plate 134 to conceal the members contained therein.

When the improved personal hygiene device described above is to be used, the cover 134 is opened and the nozzle 118 withdrawn therefrom. The nozzle 118 may be extended outwardly from the receptacle 130 through a distance limited by the length of the hose 38 upon the reel 58. The spring 88 incorporated in the reel 58 will automatically rewind the hose 82 thereon and will retract the nozzle 118 and the members adjacently associated therewith into the position illustrated in Fig. 3. Returning the cover 134 to its closed position removes the device from sight.

Fig. 1 illustrates the positioning and incorporation of the above described device into a water closet 136 adjacent a bathroom fixture, such as the commode 138. All that may be externally ascertained is a cover member 140, which will be of a color and surface finish similar to that of the water closet 136.

Fig. 2 illustrates the positioning and incorporation of the above described device into another type of bathroom fixture, such as the bathtub 142. As in the case of Fig. 1 above, all that may be externally ascertained is a cover member 144 which will be of a color and surface finish similar to that of the bathtub 142.

Having thus described the invention, I claim:

1. In combination with a bathroom fixture having a water drainage system, a concealed bathroom appliance comprising, a recessed re-

ceptacle embedded in the surface of said fixture, a water mixing chamber disposed adjacent said receptacle and within said fixture, a hot water supply and a cold water supply connected to said mixing chamber, valve means intermediate said chamber and said hot and cold water supply for proportioning the amounts of hot and cold water introduced into said chamber, manual control means for said valve means contained within said receptacle, a reel member disposed within said fixture, a length of flexible tubing coiled upon said reel member having its forward end adapted to be withdrawn from said reel member and retracted thereto, tensioning means included in said reel member for rewinding the tubing thereon and for maintaining tension on the tubing when withdrawn from said reel member, water passage means connecting said chamber and said tubing, nozzle means removably secured to the forward end of the tubing and positionable in said receptacle, passage means through said fixture connecting said receptacle with the interior of said fixture for movement of said tubing therethrough, and a manually displaceable closure member mounted on the surface of said fixture adjacent said receptacle for covering said recessed receptacle when said appliance is not in use.

2. The appliance in accordance with claim 1 wherein said removably secured nozzle means includes a nozzle member, a mounting member for said nozzle member connected to the forward end of said tubing, and a rotatable joint intermediate said nozzle member and mounting mem-

ber for permitting movement of said nozzle member relative to said mounting member.

3. The appliance in accordance with claim 1 including a medicament chamber contained within said nozzle means and disposed in the path of the water flow therethrough and straining means cooperating therewith to prevent undesired entrainment of undissolved medicament in said water flow.
